(57) **CLAIM**

The ornamental design for a pedestal for a lavatory, as shown and described.

DESCRIPTION

FIG. 1 is a front, right side, top perspective view of a pedestal for a lavatory showing our new design and being shown environmentally as supporting a lavatory shown in phantom;

FIG. 2 is a top plan view thereof;

FIG. 3 is a front elevational view thereof;

FIG. 4 is a right side elevational view thereof;

FIG. 5 is a bottom plan view thereof;

FIG. 6 is a rear elevational view thereof; and,

FIG. 7 is a left side elevational view thereof.
